CLAIM

The ornamental design for a siren horn housing, as shown and described.

DESCRIPTION

FIG. 1 is a top plan view of a siren horn housing showing my new design, the broken line disclosure of a sound producing driver being for illustrative purposes only.

FIG. 2 is a front elevational view thereof;

FIG. 3 is a bottom plan view thereof, a driver therefor being indicated in broken lines for illustrative purposes only;

FIG. 4 is a rear elevational view thereof;

FIG. 5 is a side elevational view thereof, a driver therefor being indicated in broken lines for illustrative purposes only, the other side being a mirror image of the side shown; and

FIG. 6 is a sectional view thereof on the line 6—6 of FIG. 1, a driver therefor and a sound reflective reentrant member being indicated in broken lines for illustrative purposes only.

FIG. 4

FIG. 5

FIG. 6
